REFRIGERATION SYSTEM

Wayland R. Miller, Nashotah, Wis., assignor to
 Minneapolis-Honeywell Regulator Company,
 Minneapolis, Minn., a corporation of Delaware

Application October 15, 1936, Serial No. 105,841

6 Claims.

(Cl. 62—6)

This invention relates to refrigeration control devices and more particularly to an arrangement for automatically and proportionately varying the capacity of a refrigeration compressor in accordance with the prevailing load.

In refrigeration systems of large capacity, such for instance as those employed in air conditioning systems, or cold storage plants, the refrigeration load varies considerably from period to period, due to changes in weather conditions, and also due to changes in heat emission within the enclosure, such as caused by changes in the number of persons present or changes in operation of machinery within the enclosure. Where mechanical refrigerating systems are employed, it has been customary to meet these changes in load by changing the speed of the compressor, by varying the number of compressors in operation, or by throttling. These various control schemes while being satisfactory in some respects are unsatisfactory in others. The changing of the compressor speed involves complicated and expensive apparatus and precludes the use of synchronous motors which are highly desirable from a power rate viewpoint. The changing of the number of compressors in operation is not feasible where large units are employed, as the control secured is not flexible, and involves very complex control apparatus in order to secure automatic operation. The throttling method while being simpler than the other methods mentioned, however has the serious disadvantage of being uneconomical, due to the large loss of energy occurring when the refrigeration load is light.

It is an object of my invention, therefore, to provide an automatic control device for varying the capacity of a refrigeration compressor without changing its speed, and which does not materially affect the efficiency thereof.

A further object of my invention is to provide a flexible control arrangement which is rugged in construction and simple in operation and which automatically balances the capacity of a compressor against the load it must carry.

Another object is to maintain a constant pressure in the suction line of a compressor by automatically and proportionately varying the capacity of the compressor to meet the changes in suction pressure.

A further object is to control the operation of an air conditioning system by varying the capacity of the refrigeration system compressor proportionately with the load upon the system.

Another object is to maintain a constant pres-

sure in the suction line of a compressor by automatically and proportionately varying the capacity thereof, and to automatically vary the pressure maintained in accordance with a condition affecting or affected by the operation of the compressor, such for instance as the humidity of a space.

Other objects will appear as this description proceeds.

For a full understanding of my invention, reference is made to the accompanying drawing, in which the single figure diagrammatically illustrates an air conditioning system to which one form of my invention is applied.

Reference character 1 indicates an air conditioning chamber in which is located a cooling coil 2. Chamber 1 communicates at one end with the space 3 to be conditioned. At its other end the chamber 1 communicates with a fan 4 which discharges through a duct 5 into the space 3. While for the sake of clearness I have not illustrated other air conditioning devices such as air washers, filters, reheaters, etc., it is to be understood that such apparatus may be employed. In order to supply liquid refrigerant to coil 2 and to withdraw gaseous refrigerant therefrom, I have shown a compressor generally indicated at 6. While I have illustrated this compressor as being of the double acting reciprocating type it is to be understood that any type of positive action compressor may be employed. Compressor 6 is provided with a branched discharge pipe 7 which discharges into a condenser 8. A pipe 9 leads from the outlet of condenser 8 to the expansion valve 10 which is located at the inlet of coil 2. The outlet of the evaporating coil 2 is connected by a branched pipe 11 to each end of the compressor cylinder.

Connected to each end of the compressor cylinder are a pair of clearance pockets generally designated at 13 and 14. Clearance pocket 13 is connected to the upper end of the compressor cylinder by means of a conduit 15, while clearance pocket 14 is connected to the lower end of the cylinder by conduit 16. Each clearance pocket is formed of a cylinder block 18 having bored therein a cylindrical chamber 19. Fitted into each chamber 19 is a piston 20 which is secured to a piston rod 21 having at its end a gear rack 22. The clearance pockets 13 and 14 are displaced from each other a distance sufficient to accommodate a pinion gear 25 which cooperates with each rack. Movement of pinion 25 in a clockwise direction causes the pistons to be moved away from each other, thereby reducing the volume of the

chambers 19 which are in communication with the compressor. Movement of pinion 25 in the opposite or counter-clockwise direction moves the pistons towards each other, thereby increasing the volume of the chambers which are in communication with the compressor. Each cylinder block 18 is fitted with a cylinder head 26. Each cylinder head is formed with an opening for the piston rod, this opening being fitted with a packing gland 27 for preventing the escape of refrigerant from the clearance pocket.

By varying the volume of the clearance pockets the output of the compressor may be controlled. As is well known, the volumetric efficiency of a compressor is dependent, among other things, upon the clearance volume. If the clearance volume is zero the quantity of gas which will be handled upon each stroke of the compressor will be equal to the piston displacement. If there is clearance, however, a quantity of gas sufficient to fill the clearance volume must remain in the compressor cylinder after each stroke has been completed. This gas must naturally be at a pressure equal to or slightly above the discharge pressure of the compressor. At the beginning of the suction stroke this gas will expand and must expand to a point slightly below the suction pressure before gas will be drawn from the suction line into the compressor cylinder. The effect of clearance, therefore, is to reduce the quantity of refrigerant which will be handled by the compressor per stroke. The greater the clearance volume, the more gas will be trapped in the compressor at the end of each stroke and hence the further the piston must move on its suction stroke before gas will be drawn from the suction line. Thus by increasing the clearance volume the capacity of the compressor may be reduced while by decreasing the clearance volume the capacity may be increased. Rotation of the pinion 25 in a clockwise direction, therefore, acts to increase the capacity of the compressor while rotation of the pinion in the opposite direction will decrease the compressor capacity.

By varying the clearance volume in the manner described the compressor capacity may be varied even though it is operating at constant speed, and this variation in capacity is secured without a substantial loss in efficiency. The gas which is trapped in the clearance pockets at the end of each stroke expands when the suction stroke begins and in this manner returns to the piston the energy imparted to it during the compression stroke. The only loss in energy is due to a small amount of throttling in the connecting conduits 15 and 16 and due to friction between the molecules of the gas. This loss will not be very large as compared with the output of the compressor, hence the variation in output is not accompanied by a material change in efficiency.

While for the sake of clearness I have shown the clearance pockets of somewhat exaggerated size and as being connected to the compressor by relatively long conduits, it is to be understood that in practice the clearance pockets would be placed as close to the compressor cylinder as possible in order to avoid excessive uncontrolled clearance volume.

Pinion 25 is secured to a shaft 30. This shaft in turn is secured to a gear 31 of a gear train generally indicated at 32. The end of this gear train comprises a gear 33 cooperating with a worm gear 34. Gear 34 is carried by shaft 35 which also carries armatures 36 and 37 of induction

type electric motors. Field coil 38 cooperates with the armature 36 and field coil 39 cooperates with the armature 37. These coils are arranged to cause their respective armatures to rotate in opposite directions. Thus by energizing field coil 38 worm gear 34 will be rotated in one direction while by energizing the coil 39 the worm gear will be rotated in the opposite direction. Specifically, energization of coil 38 causes rotation of the gear 34 in a counter-clockwise direction as viewed from its outer end, while energization of coil 39 causes the gear 34 to be rotated in a clockwise direction.

Energization of field coils 38 or 39 is controlled by a relay generally indicated as 40. This relay comprises two actuating coils 41 and 42 connected together. Their opposite ends are connected across the secondary 44 of a step-down transformer 45 by means of wires 46 and 47. The primary 48 of transformer 45 is connected across line wires 49 and 50. In the magnetic field of coils 41 and 42 is located an armature or plunger 51 which is connected by means of a rod 52 with a switch arm 53. Switch arm 53 is pivoted at 54 and cooperates with two contact points 55 and 56. When plunger 51 is moved to the right under the action of coils 41 and 42, the switch arm 53 is moved to engage contact 56. When the plunger moves in the opposite direction the switch arm 53 engages with the contact 55. When plunger 51 is in its midposition the switch arm 53 is likewise in a midposition and is not engaged with either contact. Switch arm 53 is connected to the line wire 49 by means of a wire 59. Contact 56 is connected by means of a wire 60 with one terminal of the limit switch 61. The other terminal of limit switch 61 is connected by wire 62 with one end of the motor field coil 38. Contact 55 is connected by means of a wire 63 to one terminal of a limit switch 64, the other terminal of this switch being connected to one end of the motor field 39 by means of a wire 65. The other ends of the motor fields 38 and 39 are connected together and by means of a wire 66 are connected to the line wire 50. It will be seen, therefore, that when contact arm 53 engages contact 56 the motor field 38 is energized by a circuit as follows: line wire 49, wire 59, contact arm 53, contact 56, wire 60, limit switch 61, wire 62, field coil 38 and wire 66 to line wire 50. Similarly, when contact arm 53 engages contact 55 the field coil 39 is energized by the following circuit: line wire 49, wire 59, contact arm 53, contact 55, wire 63, limit switch 64, wire 65, field coil 39, and wire 66 to line wire 50.

The limit switches 61 and 64 are illustrated as comprising a fixed blade 70 and a movable blade 71, these blades carrying cooperating contacts. The movable blade 71 of each switch is arranged to be actuated by a tripping member 72 which is mounted on the shaft 30. These switches act merely to stop their respective motors whenever the pistons 20 are moved to an extreme position. Thus, when contact arm 53 engages contact 56 the motor field 38 will be energized, causing rotation of the gear 34 in a counterclockwise direction, this resulting in movement of the pistons 20 to decrease the volume of the chambers 19, and so long as contact 53 remains engaged with contact 56, the pistons will be moved until they reach the end of their travel and at this point the tripping member 72 will engage limit switch 61, thus breaking the motor operating circuit. In a similar manner, when contact arm 53 engages contact 55 the pistons will be moved in a

- direction to increase the volume of chambers 19, and the energizing circuit for motor 39 will be broken by limit switch 64 when the pistons 20 reach the end of their travel if switch arm 53 has not disengaged from contact 55 meanwhile.
- Located in the space 3 is a humidostat generally indicated as 79. This instrument comprises a bell crank lever 80 having a contact arm 81, an actuating arm 83, and being pivoted at 82.
- Below the actuating arm 83 and connected thereto by a suitable link is a humidity responsive device consisting of a plurality of strands 84a of hair or other moisture responsive material, these strands being secured together at each end by means of clamping members 84 and 85. The lower clamping member 84 is secured to a suitable fixed element as 86 while the upper clamping member 85 is secured to the bell crank lever arm 83. A tension spring 87 is connected at one end to the contact arm 81, and at its other end is secured to a suitable fixed element, this spring serving to bias the bell crank lever 80 against the action of the humidity responsive elements 84a, thereby maintaining such elements under tension. The contact arm 81 of the bell crank lever is arranged to contact with a resistance element 88. Upon an increase in humidity, the strands of hair 84a will expand, thereby permitting the spring 87 to cause rotation of contact arm 81 across the resistance element in a clockwise direction. Conversely, a decrease in humidity will cause shrinking of the strands of hair 84a causing rotation of the contact arm 81 in a counter-clockwise direction.
- Connected to the suction line 11 is a pressure responsive device generally indicated at 90. This device comprises an expandable and contractible bellows 91 having one end thereof connected to the suction line 11 by means of a tube 92. Fixed to the other end of the bellows 91 is an actuating arm 93 which is pivotally connected at 94 to a contact arm 95. Contact arm 95 is pivoted at 96 and is arranged to wipe across a potentiometer resistance 97. Upon an increase in pressure in the suction line 11 the bellows 91 will expand, thus causing the contact arm to be rotated in a clockwise direction across the resistance element 97. Conversely, a decrease in pressure will cause the bellows 91 to contract, this resulting in the contact arm 95 being moved in a counter-clockwise direction across the resistance element 97.
- The left-hand end of resistance element 97 is connected to the right-hand end of the relay coil 42 by means of wires 99, 100, and protective resistance 101. The right-hand end of resistance element 97 is connected by a wire 102 and protective resistance 103 with the left-hand end of the relay coil 41. The left-hand end of the humidostat resistance 88 is connected by means of wires 104, 105, 100 and protective resistance 101 with relay coil 42, while the right-hand end of said resistance is connected by means of wires 106, 107, and protective resistance 103 to the left-hand end of relay coil 41. It will be seen, therefore, that the potentiometer resistance element 88 of the humidostat 80 and the corresponding resistance element 97 of the pressure responsive device 91 are connected in parallel across the relay coils 41 and 42. Contact arm 81 is connected by a wire 110 to a rheostat 111 which is in turn connected to wire 112 which leads to the junction of coils 41 and 42. The contact arm 95 of the pressure responsive device 91 is similarly connected to the junction of relay coils 41 and 42 by means of a wire 113 which joins wire 112. The contact arms 81 and 95 are therefore connected in parallel to the junction of relay coils 41 and 42.
- Mounted upon the shaft 30 is a contact arm 115 of a balancing potentiometer generally indicated at 114. Contact arm 115 is connected by means of a wire 116, rheostat 117 and wire 118 to the wire 112 and is therefore connected to the junction of relay coils 41 and 42 in parallel with the contact arms 81 and 95 of the humidostat and pressure responsive device respectively. The upper end of the resistance coil 120 of the balancing potentiometer 114 is connected by wire 121 to wire 107 and hence to the left end of relay coil 41, while the lower end of the resistance 120 is connected by wire 122 to the wire 105 and hence to the right end of relay coil 42. The balancing potentiometer 114 is therefore connected in parallel to the relay coils 41 and 42 along with the potentiometers of the humidostat 80 and pressure responsive device 90.
- ### Operation
- With the parts in the position shown, the contact arm 81 is engaging the center of resistance 88 while the contact arm 95 is engaging the center of its resistance 97. Contact finger 115 is also engaging the center of balancing resistance 120. Under this condition the relay coils 41 and 42 will be equally energized, due to the fact that they are connected in series across the secondary 44 of the transformer 45 and also due to the fact that no current is flowing to or from the junction of coils 41 and 42 owing to the intermediate positions of the three contact fingers. If the pressure in the suction line 11 should increase, the expansion of the bellows 91 will cause movement of the contact finger 95 in a clockwise direction across the resistance 97. As this contact finger 95 is connected to the junction of coils 41 and 42, the movement thereof in a clockwise direction will decrease the portion of the potentiometer resistance which is in parallel with the coil 41 and increase the portion of the potentiometer resistance which is in parallel with the relay coil 42. Therefore, a part of the current which had been flowing through coil 41 will flow through the right-hand portion of the resistance element 97. Similarly, a part of the current which had been flowing through the left-hand portion of resistance 97 will flow through the relay coil 42. Thus a clockwise movement of the contact arm 95 has the effect of decreasing the energization of coil 41 and increasing the energization of coil 42. As the energization of coil 42 becomes greater than that of coil 41, the armature 51 will be moved towards the right, thus moving the contact arm 53 towards contact 56. Upon further increase in pressure in pipe 11, contact arm 53 will be moved closer to contact 56. When the increase in pressure is sufficient, the contact arm 53 will engage contact 56. This will cause energization of the motor field 38 and will cause rotation of the worm gear 34 in a direction to reduce the volume of chambers 19. As the pistons are being thus moved, the contact finger 115 will be rotated in a clockwise direction across the resistance element 120. This action will act to increase the portion of resistance 120 which is in parallel with the relay coil 41 and to decrease the portion of the resistance 120 which is in parallel with the relay coil 42. This will act to decrease the flow of current through coil 42 and to increase the flow through the relay coil 41. When the contact

finger 115 is moved sufficiently across its cooperating resistance the energization of coils 41 and 42 will again become equalized, thus causing the armature 51 to move the contact finger 53 to its mid-position thus breaking the energizing circuit for field 38 and causing the motor to stop. Due to the worm gear drive, the pistons 20 will be locked in their new positions. As they have been moved to reduce the volume of the chambers 19, the clearance volume of the compressor will have been decreased thus increasing the volumetric efficiency of the compressor and causing it to assume a greater load. An increase in pressure, therefore, acts to adjust the clearance volume so as to cause the compressor to carry the increased load as indicated by the increase in pressure.

Upon a decrease in pressure in the suction line 11, the bellows 91 will contract thus causing the contact arm 95 to be moved in a counter-clockwise direction across the resistance element 97. This will have the effect of increasing the energization of relay coil 41 and decreasing the energization of relay coil 42. This effect will cause the armature 51 to be moved towards the left thus moving the contact arm 53 towards the contact 55. When the decrease in pressure has become sufficient, armature 51 will be further moved to the left and bring contact arm 53 into engagement with contact 55. This action will energize the motor field 39, thus causing the pinion 25 to be rotated in a clockwise direction, this action moving the pistons 20 towards each other and increasing the clearance volume. In the manner stated previously, this increase in clearance volume will reduce the capacity of the compressor. While the pistons 20 are being moved towards each other, the contact arm 115 is rotated in a counter-clockwise direction. This results in decreasing the portion of resistance 120 which is in parallel with the relay coil 41, and in increasing the portion of the resistance which is in parallel with the coil 42. When the movement of contact finger 115 in the clockwise direction becomes sufficient to cause balancing of the current flows in coils 41 and 42, the armature 51 will be moved towards the right thus moving contact arm 53 from engagement with contact 55, thereby opening the operating circuit for motor 39.

It will be seen, therefore, that an increase in pressure in the suction line 11 will cause the pistons 20 to be moved in a direction which reduces the clearance volume of the compressor and that the amount of such movement will be proportional to the increase in pressure. Similarly, upon a drop in pressure in the suction line 11, the pistons will be moved in a direction to increase the clearance volume and the amount of movement will be proportional to the fall in pressure.

The action of the rheostat 117 which is interposed between the junction of coils 41 and 42 and the contact finger 115 of the balancing potentiometer 114 is to reduce the sensitivity of said potentiometer. This rheostat in effect chokes the flow of current through the contact finger 115 thus necessitating a relatively large movement of said contact finger across the resistance 120 to effect a relatively small variation in the energization of coils 41 and 42. Thus when contact finger 95 of the pressure responsive device 90 moves across this resistance 97 it effects an unbalancing of the energization of coils 41 and 42. This, in the manner previously described, causes energization of either motor field 38 or 39, this resulting in rotation of contact finger 115 in a

direction to rebalance the energization of relay coils 41 and 42. Due to the choking action of rheostat 117, contact finger 115 must move across its resistance 120 in order to rebalance the energization of coils 41 and 42, a greater distance than the movement of the contact arm 95 moved to cause the initial unbalancing. Thus by properly adjusting the rheostat 117 a slight movement of contact arm 95 may cause the balancing potentiometer 114 to traverse its complete range in order to rebalance the energization of coils 41 and 42. In this manner the operating range of the pressurestat potentiometer may be made less than its total range. That is, a movement of contact arm 95 through but part of its range may cause the pistons 20 to be moved from one extreme position to the other.

Upon an increase in humidity the contact finger 81 will be caused to move across the resistance 8 in a clockwise direction. This will have the effect of decreasing the energization of relay coil 41 and increasing the flow of current through relay coil 42. When the change in humidity becomes sufficient, relay coil 42 will be energized sufficiently greater than relay coil 41 as to cause the armature 51 to move to the right and cause contact arm 53 to engage the contact 56. This will cause energization of the motor field coil 39 thus causing rotation of the worm gear 34 in a direction which acts to move the pistons 20 away from each other, thereby decreasing the clearance volume of the compressor. At the same time, the contact finger 115 of the balancing potentiometer 114 will be moved in a clockwise direction across the resistance 120. This action will act to decrease the energization of relay coil 42 and increase the current flow in relay coil 41. When the movement of contact finger 115 becomes sufficient to rebalance the current flow through the relay coils, armature 51 will swing back towards its mid-position, thus breaking the motor actuating circuit. In this manner an increase in humidity causes the clearance volume of the compressor to be decreased, thereby causing the capacity of the compressor to be increased. This results in a decrease in pressure in the evaporating coil 2 which causes its temperature to be lowered. Due to this lower temperature an increased amount of moisture will be condensed on the cooling coil 2, thereby removing moisture from the air and lowering its relative humidity. An increase in humidity therefore acts to lower the coil temperature and pressure and the amount that the temperature and pressure is lowered is proportional to the humidity increase. That is, the greater the increase in humidity the lower the coil pressure that will be maintained.

Upon a decrease in humidity, contraction of the humidity responsive strands 84 will cause rotation of the contact finger 81 in a counter-clockwise direction. This action results in decreasing the current flow through the relay coil 42 and in increasing the current flow through relay coil 41. This will result in the armature 51 being moved to the left, thereby bringing contact arm 53 into engagement with the contact point 55. This will cause energization of the motor field coil 39, thereby moving the pistons 20 towards each other to increase the compressor clearance volume. Simultaneously the contact finger 115 will be moved in a counter-clockwise direction across resistance 120, this action tending to balance the current flows in relay coils 41 and 42. When the movement of contact finger 115 has become sufficient to cause balancing of the current flows in

said relay coils, the contact arm 53 will be disengaged from the contact point 55 thereby stopping the motor at this point. A decrease in relative humidity, therefore, acts to decrease the capacity of the compressor and this reduction in capacity will be proportional to the decrease in humidity. The reduction in the compressor capacity results in the pressure rising in the suction line 11 and evaporating coil 2 thereby causing the temperature of the coil 2 to increase, which causes it to remove less moisture from the air passing thereover.

It will be observed that rheostat 111 is interposed between the contact finger 81 and the junction of relay coils 41 and 42. This rheostat acts to decrease the sensitivity of the humidostat 80. Due to this decrease in sensitivity the effect of the humidostat 80 upon the system may be controlled.

As noted herebefore, the effect of the rheostat 111 is to reduce the sensitivity of the balancing potentiometer 120 thereby causing the operating range of the pressurestat potentiometer to be less than its total range. In other words, a movement 25 of the contact finger 95 across but a portion of resistance 97 will cause movement of the pistons 20 from one extreme to the other. The center of the operating range of the pressurestat potentiometer is the position of the contact finger 95 which causes the balancing potentiometer contact finger 115 to assume a mid-position. Should the contact finger 95 move clockwise from this operating range center it will cause movement of contact finger 115 in a similar direction to balance the effect thereof. Similarly, should the contact finger 95 move to the left of this operating range center, corresponding movement of the balancing contact finger 115 will take place.

The effect of the humidostat 80 is to shift the location of the pressurestat operating range within its total range. It will be observed that the effect of the humidostat on the system under an increase in humidity is similar to the effect of the pressurestat 90 under an increase in pressure. In other words, an increase in humidity will cause the relay coil 42 to be energized to a greater extent than the relay coil 41 and an increase in pressure will have this same effect. When the humidostat 80 is in its mid-position the center of the operating range of the pressurestat potentiometer will coincide with the center of its total range. Should the humidity increase, the contact finger 88 will be moved clockwise, thereby decreasing the current flow in relay coil 41 and increasing the current flow in relay coil 42. In order for the pressurestat potentiometer to rebalance the current flows in relay coils 41 and 42, the contact finger 95 must move in a counter-clockwise direction across resistance 97, which requires a decrease in pressure in the suction line 11. The effect of a rise in humidity, therefore, is to shift the center of the operating range of the pressurestat potentiometer to the left, thereby causing it to maintain a lower pressure in the evaporator. Similarly, a decrease in humidity will cause contact finger 81 to move in a counter-clockwise direction across resistance 88, thereby increasing the current flow in relay coil 41 and decreasing the current flow through relay coil 42. In order for the pressurestat potentiometer to rebalance the relay the contact finger 95 must be moved in a clockwise direction across the resistance 97, this requiring an increase in pressure in the suction line 11. The effect of a decrease in humidity, therefore, is to shift the

center of the operating range of the pressurestat potentiometer to the right, thereby causing it to maintain a higher pressure in the evaporating coil 2.

The effect of the humidostat, therefore, is to shift the operating range of the pressurestat potentiometer within its total range to cause a higher pressure to be maintained in the evaporating coil 2 when the humidity is low and to cause progressively lower pressures to be maintained in the evaporating coil as the humidity increases.

In view of the foregoing it will be apparent that I have provided an arrangement for modulating the capacity of a constant speed compressor in order to cause it to operate to carry the desired load, this arrangement being extremely flexible and causing variation of the compressor operation without sacrificing efficiency for any load condition from zero to full load. While I have illustrated my invention in connection with a compressor for an air conditioning system and in which the compressor is controlled in accordance with the pressure in the suction line, and in accordance with humidity in the space to be conditioned, it is to be understood that my invention may be applied to any positive displacement type of compressor and may be responsive to other factors related to the compressor load, such, for instance, as the temperature in the conditioned space. It is also to be understood that the control device may be positioned in accordance with suction line pressure alone, humidity alone, or in accordance with any other condition affecting or affected by the load.

As many modifications of my invention will suggest themselves to those skilled in the art, I wish to be limited only by the scope of the appended claims and the prior art.

I claim as my invention:

1. In an air conditioning system, in combination, an evaporator in heat exchange relationship with a space to be conditioned, means for supplying liquid refrigerant to the evaporator, a positive displacement compressor connected to said evaporator, movable means associated with the interior of the compressor for varying the volume of refrigerant drawn into the compressor per cycle thereby varying its capacity, positioning means for gradually positioning said movable means, said positioning means including a device influenced by the temperature at which the liquid refrigerant in the evaporator evaporates and acting to position said movable means in a manner to increase the volume of refrigerant drawn into the compressor upon increase in said evaporating refrigerant temperature and to decrease the volume of refrigerant drawn into the compressor upon decrease in said evaporating refrigerant temperature, and a controller responsive to a condition of the air in said space which is affected by said evaporator, said controller adjusting said positioning means for varying the evaporating temperature of the refrigerant in accordance with variations in said space condition.

2. In an air conditioning system, in combination, an evaporator in heat exchange relationship with a space to be conditioned, means for supplying liquid refrigerant to the evaporator, a positive displacement compressor connected to said evaporator, means for varying the clearance volume of the compressor, positioning means for gradually positioning said clearance volume varying means, said positioning means including

- 5 a device influenced by the temperature at which liquid refrigerant in the evaporator evaporates and acting to position said clearance volume varying means for decreasing the clearance volume upon increase in said evaporating refrigerant temperature and to increase the clearance volume upon decrease in said evaporating refrigerant temperature, and a controller responsive to a condition of the air in said space which is 5
10 affected by said evaporator, said controller adjusting said positioning means for varying the evaporating temperature of the refrigerant in accordance with variations in said space condition.
- 15 3. In an air conditioning system, in combination, an evaporator in heat exchange relationship with a space to be conditioned, means for supplying liquid refrigerant to the evaporator, a positive displacement compressor connected to 20 said evaporator, movable means associated with the interior of the compressor for varying the volume of refrigerant drawn into the compressor per cycle thereby varying its capacity, positioning means for gradually positioning said movable means, said positioning means including a device influenced by the temperature at which the liquid refrigerant in the evaporator evaporates and acting to position said movable means in a manner to increase the volume of refrigerant 25 drawn into the compressor upon increase in said evaporating refrigerant temperature and to decrease the volume of refrigerant drawn into the compressor upon decrease in said evaporating refrigerant temperature, and a controller responsive to the moisture in the air in said space, said controller adjusting said positioning means in a manner to lower the evaporating temperature of the refrigerant as the moisture in the air increases and to raise the evaporating temperature 30 as the moisture in the air decreases.
- 40 4. In an air conditioning system, in combination, an evaporator in heat exchange relationship with a space to be conditioned, means for supplying liquid refrigerant to the evaporator, a positive displacement compressor connected to 45 said evaporator, movable means associated with the interior of the compressor for varying the volume of refrigerant drawn into the compressor per cycle thereby varying its capacity, positioning means for gradually positioning said movable means, said positioning means including a device influenced by the temperature at which the liquid refrigerant in the evaporator evaporates and acting to position said movable means in a manner to increase the volume of refrigerant 50 drawn into the compressor upon increase in said evaporating refrigerant temperature and to decrease the volume of refrigerant drawn into the compressor upon decrease in said evaporating refrigerant temperature to thereby maintain the evaporating temperature of the refrigerant substantially constant, the evaporating temperature influenced device having a total range of operation greater than necessary for maintaining the

5 evaporating temperature constant, and a controller responsive to the condition of the air in said space, said controller being arranged to shift the operating range of said device within its total range to cause different evaporating temperatures to be maintained for different values of said condition.

5. In an air conditioning system, in combination, an evaporator in heat exchange relationship with a space to be conditioned, means for 10 supplying liquid refrigerant to the evaporator, a positive displacement compressor connected to said evaporator, movable means associated with the interior of the compressor for varying the volume of refrigerant drawn into the compressor 15 per cycle thereby varying its capacity, a reversible electric motor for gradually positioning said movable means, control means for said reversible electric motor including a switching means for selectively causing said motor to travel 20 in either direction or to remain stationary, said control means also including a device influenced by the temperature at which the liquid refrigerant in the evaporator evaporates for controlling said switching means, said control means acting 25 to position said movable means in a manner to increase the volume of refrigerant drawn into the compressor upon increase in said evaporating refrigerant temperature and to decrease the volume of refrigerant drawn into the compressor 30 upon decrease in said evaporating refrigerant temperature, and a controller responsive to a condition of the air in said space which is affected by said evaporator, said controller acting to adjust said control means for varying the evaporating temperature of the refrigerant in accordance with variations in said space condition.

6. In an air conditioning system, in combination, an evaporator in heat exchange relationship with a space to be conditioned, means for 40 supplying liquid refrigerant to the evaporator, a positive displacement compressor connected to said evaporator, an adjustable clearance pocket for said compressor for varying the clearance volume of said compressor, a reversible electric motor for 45 adjusting said clearance pocket, control means for said reversible electric motor including a switching means for selectively causing said motor to travel in either direction or to remain stationary, said control means also including a device influenced by the temperature at which the liquid refrigerant in the evaporator evaporates for controlling said switching means, said control means acting to cause decrease in the clearance volume upon increase in said temperature 50 and to cause increase in clearance volume upon decrease in said temperature and a controller responsive to a condition of the air in said space which is affected by said evaporator, said controller acting to adjust said control means for 55 varying the evaporating temperature of the refrigerant in accordance with variations in said space condition.
